UNITED STATES PATENT OFFICE

2,173,919

COMMODITY WRAPPER

Jonas Schuchat, Chicago, Ill.

Application January 27, 1937, Serial No. 122,512

4 Claims. (Cl. 206—44)

My present invention relates generally to improvements in the art of manufacturing wrappers for sundry articles, and relates more specifically to improvements in the construction of commodity 5 wrappers especially adapted for the enclosure of relatively flat and approximately circular articles such as pies, confections or the like.

Generally defined, an object of my present invention is to provide an improved wrapper for 10 commodities such as pies, which is simple in construction and extremely effective in use.

In my prior Patent No. 2,005,208, granted June 18, 1935, I have shown an improved wrapper for pastries, such as a pie resting in a relatively 15 rigid pie plate having a resilient rim, the wrapping comprising a transparent sheet of thin flexible material covering the pie extending downwardly beyond the peripheral rim of the supporting plate, and an endless flexible polygonal band member encircling the plate and having 20 therein a series of elongated slots for receiving successive portions of the plate rim and for folding the covering sheet about these rim portions. While this prior wrapper when once properly applied, is extremely effective and commercially 25 satisfactory, the spring action of the plate rim which is relied upon to produce clamping as the band member is lowered vertically over the covering sheet and the rim of the plate, makes it rather 30 difficult to apply the clamping band to the assemblage and sometimes causes the bands to burst. I have found that this spring action of the plate rim can be practically obviated, by properly forming the retainer band, and that the 35 wrapping structures may also be more readily assembled without breaking the bands and without distributing the position of the covering sheet 40 relative to the enwrapped article.

It is therefore a more specific object of my 45 present invention to provide an improved clamping band for wrapping assemblages of the above described type, which may be conveniently applied and which will effectively retain the wrapper in assembled condition.

Another specific object of my present invention 50 is the provision of a new and useful commodity wrapper which is adapted for use in wrapping any relatively flat and generally circular article resting upon a relatively rigid support, so that the article will be effectively protected and concealed but will still be visible to prospective purchasers.

A further specific object of this invention is to 55 provide an improved wrapper having an improved assembly band of the continuous and locally slotted type formed so that the article itself will

automatically guide the band toward finally assembled position.

Still another specific object of the invention is to provide a simple and durable commodity wrapper which may be manufactured at moderate cost, 5 and which is also applicable to a wrapper having a printed covering so that the position of the printing relative to the article will not be disturbed during application of the wrapping.

These and other objects and advantages of my 10 present invention will be apparent from the following detailed description, and some of the novel features of wrapper construction shown but not 15 specifically claimed herein, form the subject of my said prior patent.

A clear conception of several embodiments of my present improvement, and of the mode of constructing and of utilizing commodity wrappers made in accordance with this invention, may be had by referring to the drawings accompanying 20 and forming a part of this specification, wherein like reference characters designate the same or similar parts in the various views.

Fig. 1 is a full top view of a finally assembled 25 pie wrapper embodying my present invention;

Fig. 2 is a transverse vertical section through the pie and wrapper of Fig. 1, taken along the irregular line 2—2;

Fig. 3 is a development of a fragment of the outer clamping band of the pie wrapper, looking 30 toward the outside thereof;

Fig. 4 is a horizontal section through the clamping band of Fig. 3, taken along the line 4—4;

Fig. 5 is a fragmentary bottom view of the assemblage of Fig. 1;

Fig. 6 is a full top view of a chocolate nut confection enwrapped in one of my improved commodity wrappers;

Fig. 7 is a transverse vertical section through the assemblage of Fig. 6, taken along the irregular line 7—7;

Fig. 8 is an outside development of a fragment of the clamping band of the modified wrapper;

Fig. 9 is a horizontal section through the clamping band of Fig. 8, taken along the line 9—9; and

Fig. 10 is a fragmentary bottom view of the assemblage of Fig. 6.

Although I have shown my improved wrapper as having been applied to only two specific kinds of substantially circular commodity, it is not intended to thereby unnecessarily restrict the scope, since some of the improved features may obviously be advantageously applied in wrappings for other objects having different shapes than those illustrated.

Referring especially to Figs. 1 to 5 inclusive, the improved pie wrapper illustrated therein, comprises in general a relatively stiff support such as a standard paper pie plate 15 for normally 5 confining and supporting the pie 16; a thin flexible sheet 17 of cellulose film or other relatively transparent material disposed over the top of the pie 16 and depending over the peripheral edge or rim 18 of the plate 15; and a continuous substantially polygonal clamping band 19 having a series of elongated slots 20 for receiving local portions of the plate rim 18 so as to clamp the adjacent portions of the sheet 17 thereagainst.

While the plates 15 are ordinarily formed of relatively heavy paper and may be discarded after the pie 16 has been consumed, the plates may be formed of metal or of any other suitable material. So far as my present improvement is concerned, the plate rim 18 need not necessarily be 10 flexible, but this rim should preferably project outwardly beyond the peripheral edge of the pie 16 in order to permit proper application of the other elements of the wrapper.

The covering or enclosure sheet 17 is preferably formed of some tenacious and relatively transparent material in order to make the enwrapped object clearly visible therethrough, and when the pie 16 or other object which is to be enwrapped, is substantially circular, the sheet 17 25 would also be of substantially circular shape and of sufficient diameter to overlap the rim 18 to a considerable extent.

The improved clamping band 19, besides being continuous and provided with the slots 20, is preferably polygonal in form before and after being applied to the assemblage, but is distortable into substantially circular shape having an internal diameter slightly greater than that of the plate rim 18, during application thereof to the package. The band 19 may be formed from a strip 30 of relatively heavy but easily distortable material such as card board, and the strip is provided with local scoring 21 and has its ends 22 permanently connected by stapling or gluing to produce the polygon which in the present disclosure is an octagon. In accordance with my improvement, the strip or band 19 is also provided with a series of notches 23 located one at the lower end of each scoring 21, and is also provided with scoring 35 24 connecting the upper ends of the successive notches 23 so as to provide an outwardly bendable tongue or flap 25 at the lower portion of each side or section of the polygon. The band 19 may also be provided with sets of inwardly extending 40 triangular projections 26 adjacent the lower medial portion of each of the slots 20, and it is to be noted that the band 19 by virtue of the scoring 21, 24 may be folded into relatively flat condition 45 for shipment in condensed form.

When it is desired to apply one of the improved wrappers to a plate 15 bearing a pie 16, it is preferable to first loosely apply the transparent covering sheet 17 so that the edge portions thereof will overlap all parts of the rim 18, whereupon 50 the retainer or clamping band 19 may be distended and lowered over the initial assemblage. The flaps 25 upon engaging the sheet 17 at the rim 18 will automatically swing outwardly about the horizontal scorings 24 and the medial portions 55 of the band sections directly above the scorings 24 will bend outwardly to permit relatively unobstructed lowering of the band 19 until the adjacent portions of the rim 18 enter the slots 20. The sections of the band 19 between the vertical 60 scorings 21 will thereafter tend to straighten and

will thus cause the resilient projections 26 and the adjacent walls of the slots 20 to engage the portions of the sheet 17 coacting with the bottom of the rim 18, as clearly shown at the right of Fig. 2. The straightening of these band sections 5 will also simultaneously cause the scorings 21 to spread away from the rim 18, thus permitting the adjacent portions of the covering sheet 17 to move away from the rim and to produce small vent openings 27 as shown at the left of Fig. 2. 10 During application of the band 19, the flaps 25 prevent shifting of the covering sheet 17 relative to the pie 16, and the wrapper when thus finally assembled, effectively conceals and protects the pie 16, while the openings 27 provide sufficient 15 venting to prevent the commodity from becoming rancid. The wrapper may obviously be readily removed by merely tearing the band 19 and by thereafter removing the covering sheet 17.

Referring more particularly to the modified embodiment of Figs. 6 to 10 inclusive, the improved chocolate-nut bar wrapper illustrated therein, comprises in general a relatively stiff support such as a flat dish or plate 30 for normally supporting the bar 31; a thin flexible sheet 25 32 of relatively transparent material disposed over the top of the bar 31 and extending downwardly beyond the rim or edge 33 of the plate 30; and a substantially polygonal and continuous clamping band 34 having a series of elongated 30 slots 35 therein for receiving local peripheral portions of the plate edge 33 so as to clamp the adjoining portions of the covering sheet 32 thereagainst.

The plate 30 may be formed of card board or 35 of any other relatively stiff material and may be round or of any other desired shape substantially corresponding to the shape of the article, but the rim edge 33 should preferably project outwardly beyond the bar 31. The covering or enclosing sheet 32 may be formed of cellulose film or other relatively transparent and relatively tough material, and should be sufficiently extensive to project well below the bottom of the supporting plate 30. 40

The improved clamping band 34 of Figs. 6 to 10 inclusive is similar to that of Figs. 1 to 4 inclusive, in that it is continuous, polygonal in shape, and is formed of relatively heavy but easily distortable material such as cardboard. The 50 band 34 also has spaced vertical scorings 36 and a notch 37 at the lower end of each of these scorings, and is provided with horizontal scorings 38 which connect the upper ends of the notches 37 to provide laterally swingable tongues or flaps 55 39. The ends 40 of the band 34 are again permanently interconnected by stapling, gluing or otherwise, and may be collapsed into relatively flat condition for shipment.

When it is desired to apply one of the modified 60 improved wrappers to a disk or plate 30 having a chocolate nut bar 31 resting thereon, the transparent covering sheet 32 should first be applied over the object and plate edge 33, whereupon the continuous clamping band 34 should be distended 65 and lowered over the initial assemblage. In order to permit convenient application of the band 34, the plate 30 may be temporarily supported upon some object such as a previously wrapped bar 31, thus elevating the plate edge 33. The 70 flaps 39 upon engaging the covering at the plate edge 33, swing outwardly about the horizontal scorings 38 and thus permit the edge 33 to bend these flaps until the edge portions of the plate 30 are eventually forced through the slots 35 as 75

the assembling operation continues, as clearly shown at the right of Fig. 7. As soon as the edge portions of the plate 30 enter the slots 35, the portions of the band 34 between the vertical scorings 36 tend to straighten and thus not only maintain the band in assembled condition, but also produce vent openings 41 at the corners of the polygon, as shown at the left of Fig. 7. The modified wrapper when thus assembled, also effectively conceals and protects the bar 31, and this wrapper may likewise readily be removed by tearing or pulling off the band 34 and thereafter removing the covering sheet 32.

From the foregoing description it will be apparent that the present invention provides an improved wrapper for pies and the like, which may be conveniently applied and removed, and which moreover effectively encloses the commodity while at the same time properly venting the enclosure. The enwrapped articles may be stacked upon each other in a most effective manner, and the improved construction of the continuous clamping bands with the lower flaps, permits rapid and effective application of these bands without danger of breaking them. The flaps, during application of the bands to the plates, provide effective guides and cause the plate edges or rims to quickly enter the slots while at the same time pulling the cover sheet taut; and when projections 26 are used, these also serve to maintain the band in taut clamped position. The projections 26 are so formed that they are relatively springy and biased inwardly, and they will not flatten into the plane of the band 19 due to collapse of this band for shipment. In some cases, it is desirable to provide the outer transparent covering sheets with printed matter or the like, and to maintain this printed matter in a definite position relative to the finally enwrapped article. The use of the lower flaps coacting with the covering and with the edge portions of the article to automatically guide the band into final position when the band is being finally applied, prevents such undesirable shifting of the outer covering and maintains the printed matter in the desired position. The improved wrapper while effectively concealing, protecting and venting the enwrapped article, permits observation thereof at all times, and the clamping bands may obviously be scored to produce polygons of any desired number of sides. The present improved wrapper has proven highly successful in actual use and may obviously be applied to various kinds of commodities.

It should be understood that it is not desired to limit the invention to the exact details of construction and to the precise mode of use, herein shown and described, for various modifications

within the scope of the claims may occur to persons skilled in the art.

I claim:

1. A commodity wrapper, comprising, a plate for directly supporting the commodity and having a peripheral rim, a flexible cover sheet disposed over the commodity and depending over said rim, and a continuous relatively wide and flexible band surrounding said plate and the marginal portion of said cover sheet, said band having a plurality of elongated slots formed to receive spaced portions of said rim and cover sheet and also having upwardly extending notches and scoring connecting the upper ends of the successive notches to provide a series of outwardly deflectable flaps normally depending from the lower edge of the band for guiding said rim portions into said slots during application of the band. 5 10 15

2. A commodity wrapper, comprising, a commodity supporting plate having a peripheral rim, a transparent cover sheet disposed above the commodity and snugly engaging local portions of said rim, and a continuous polygonal band having spaced slots for clamping the adjacent portions 20 25 of said cover sheet over said local rim portions, said band having a slit extending downwardly from the medial portion of each of said slots and an inwardly biased resilient local triangular projection adjoining each of said slits. 30

3. A commodity wrapper, comprising, a commodity supporting plate having a peripheral rim, a transparent cover sheet disposed above the commodity and snugly engaging local portions of said rim, and a continuous polygonal band having 35 spaced slots for clamping the adjacent portions of said cover sheet over said local rim portions, said band having a slit extending downwardly from the center of each of said slots and a pair of 40 inwardly biased local resilient triangular projections adjoining the central portion of each of said slits.

4. A commodity wrapper, comprising, a commodity supporting plate having a peripheral rim, a transparent cover sheet disposed above the 45 commodity and snugly engaging local portions of said rim, and a continuous polygonal band having spaced slots in the sides of the polygon for clamping the adjacent portions of said cover sheet over said local rim portions, said band 50 having upwardly extending notches between the successive slots therein and being scored from notch to notch along lines extending substantially parallel to and beneath said slots to provide depending outwardly deflectable resilient guiding 55 flaps at the several polygon sides.

JONAS SCHUCHAT.
